MICRO-HOLE LOCATOR

Nathan Zanger, Brooklyn, N.Y.

Application June 23, 1958, Serial No. 743,642

3 Claims. (Cl. 77—63)

This invention relates to an improved device for aligning work accurately and rapidly under milling and boring tools.

The improved device comprises a foundation with parallel ways in which is slidably mounted a special vise for holding and locating the work piece accurately in place. The desired position along the axis of the ways is accurately located by means of an adjustable micrometer mounted on the foundation piece in a position adapted to engage the work piece protruding from the vise jaws. The work piece is accurately located in a transverse direction by moving the work piece in the vise and using a micrometer mounted on the vise in a direction transverse to the first micrometer. Thus the transverse micrometer moves longitudinally with the vise and is ready in any longitudinal position to accurately locate the work transversely. By this construction holes can be drilled or reamed in rapid succession by a rapid adjustment of the vise longitudinally a transverse adjustment of the work piece itself in the vise jaws.

Consequently it is a primary object of this invention to provide a device whereby a plurality of holes can be drilled accurately and rapidly according to a predetermined pattern by moving a vise in parallel ways and moving the work piece in parallel vise jaws transversely disposed relative to the ways.

Another object of this invention is the provision of longitudinally movable vise jaws arranged transversely to the longitudinal direction wherein the vise includes a micrometer adapted to set the work accurately in a transverse direction relative to the vise jaws.

Additional objects and novel features of this invention will be disclosed in more detail in the following description, claims and appended drawings in which:

Figure 1 is a plan view of the foundation assembly on which the vise assembly is mounted.

Figure 2 is a longitudinal elevation of the foundation assembly.

Figure 3 is a plan view of the vise assembly.

Figure 4 is a longitudinal elevation of the vise assembly.

Figure 5 is a plan view of an assembly of the vise and foundation assembly showing a work piece clamped in place ready for a drilling operation.

Figure 6 is a transverse elevation of the assembly of Figure 5.

Figure 7 is a partial sectional view through the retaining rod showing the preferred method of affixing the vise assembly relative to the foundation assembly.

Figure 8 is a similar view depicting an alternate construction for the retaining rod.

Referring to Figures 1 and 2 the foundation assembly is seen to comprise spaced transverse end walls 10 and 11 having bearings 12 and 13. A rod 14 is rotatably mounted in the bearings 12 and 13 by means of cylindrical ends 15 and 16. The portion of rod 14 between the ends 15 and 16 is preferably of circular cross section with an axis eccentrically disposed relative to the axis of the bear-

2

ings 12 and 13 thereby causing the eccentric portion of rod 14 to wobble about the rotational axis during rotation. A handle 17 is provided to actuate the rod 14. Side walls 18 and 19 integrally connect end walls 10 and 11 and include holes 20, 21, 22, and 23 for mounting the foundation assembly on a drill work table (not shown). Walls 18 and 19 include parallel ways 24 and 25 which are accurately machined and adapted to receive and guide the vise assembly accurately in a longitudinal direction relative to the foundation assembly.

A micrometer 26 is mounted on the side of the wall 19 parallel to the ways by means of a bracket 27 provided with a bore 28. The micrometer 26 is carried by a rod 29 which is slidably mounted in bore 28 and retained in various positions by cam lock 30. The rod 29 includes an upstanding support 31 through which the micrometer projects and is referenced to. Thus the zero position of the micrometer can be obtained at varying longitudinal positions by sliding rod 29 relative to bracket 27, and then tightening the lock 30. When a desired position of the vise assembly relative to the foundation has been set via the micrometer, pins 32 and 33, whose longitudinal position is affixed by screws 34 and 35 are used to retain the desired position acting as a stop and the micrometer is backed off to prevent wear and tear on the micrometer point.

In Figures 3 and 4 the vise assembly is seen to comprise a housing 36 having an end abutment 37 provided with a threaded bore 38 which receives the screw 38. A jaw 39 having a transverse clamping surface 40 is swivelly mounted on a reduced end 41 of screw 38 and an actuating handle 42 is provided at the outer end to operate the screw. An opposing jaw 43 with an accurately machined transverse clamping surface 44 is provided opposite jaw 39. Jaw 43 projects upwardly and is integral with the base 45 of the housing 36. Thus rotation of the screw 38 advances jaw 39 towards jaw 43. A locking plate 46 interconnects spaced guide blocks 47 and 48 which slide in ways 24 and 25. The plate 46 is curved downwardly and fits in a recess in the foundation (see Figure 6). It is used to frictionally retain the vise assembly in a desired fixed position relative to the foundation as will be made clearer below.

A micrometer support bar 49 is slidably mounted in a bore 50 through jaw 43 and retained in desired transverse position by a cam lock 51. A micrometer 52 is mounted through a collar 53, attached to bar 49, and used to zero the micrometer at desired transverse locations.

A pin 54, mounted through blocks 47 and 48 is used to engage the micrometer 26 and reference the vise assembly relative to the foundation assembly.

In Figures 6 and 7, the function of locking plate 46 is seen more clearly. In order to affix the vise assembly relative to the foundation assembly, the handle 17 is rotated causing eccentric rod 14 to engage plate 46 with sufficient friction to prevent longitudinal motion of the vise assembly.

In Figure 8 an elliptical rod 14-a is used instead of an eccentrically mounted rod, thereby providing clamping action by rotation of handle 17 clockwise or counter-clockwise.

Referring to Figure 5, the operation is as follows:

The handle 17 is rotated to unlock the vise assembly and the vise assembly is moved longitudinally until the pin 54 contacts the head of micrometer 26 which has been set at the proper reading to provide the spacing between holes A and B. It is to be understood that hole B was the first hole drilled with the micrometer 26 set at zero. Having drilled hole B, the micrometer 26 is set at the reading corresponding to dimension X and the vise assembly moved so that pin 54 contacts the microm-

eter head. Jaw 39 is then loosened by means of handle 42 and the work piece W can be moved transversely. Micrometer 52 is then set to read the dimension Y and the work piece is moved between the jaws until it contacts the head of micrometer 52, whereupon the jaw 39 is again clamped against the workpiece. The drill is now centered accurately over the center of where hole A is to be formed. To make similar predetermined holes, the process is repeated with of course the proper dimensions set on the micrometer.

The use of fixed accurately machined transverse jaws to align the work piece in a transverse direction eliminates the need for aligning the vise jaws accurately at right angles to the longitudinal axis each time a hole is to be located in the transverse direction as is necessary in conventional milling or boring machines. Thus a great deal of time and effort is saved and the work is effected more accurately.

The conventional machines used for this purpose are generally not direct reading. The settings are made by rotating a handle which moves a lead screw a specific distance per turn. Therefore the operator must remember and compute the number of turns required to locate the desired position. In the instant device the distances are read directly on the micrometer thereby eliminating errors that may occur through faulty computation.

Utilization of this device in connection with the usual boring or milling tools used in small machine shops will greatly expedite the work and enable small shops to do work normally undertaken by large machine shops with complicated expensive equipment.

It is to be understood that other modifications can be effected to practice the disclosed invention without departing from the scope of the invention. All such modifications within the skill of a trained mechanic are considered as within the spirit of this invention.

Having described in detail the nature of this invention, the claims are as follows:

1. An aligning device for boring and milling machines

comprising a foundation with parallel ways and a micrometer mounted on the foundation parallel to the ways, said micrometer being longitudinally adjustable relative to the foundation, in combination with a vise slidably disposed in said ways having means for affixing the vise to the foundation at a plurality of positions along the axis of the ways, said vise including means projecting therefrom adapted to engage the said micrometer for accurately centering the vise at desired locations along the ways, 10 said vise also having a pair of jaws, one of which is movable parallel to the ways and the other jaw being fixed to the vise, said jaws having opposing transverse faces, one of which is accurately set at right angles to the way axis and adapted to clamp a workpiece securely to the vise.

2. A device as in claim 1 in further combination with a second micrometer mounted on the vise assembly along a transverse axis and adapted to engage said workpiece, the second said micrometer being mounted adjustably on the said vise whereby it can be positioned in a plurality of transverse positions enabling transverse centering of workpieces of varying dimensions.

3. A device as in claim 1 wherein the first said means comprise an eccentric rod swivelled in the foundation having bearings aligned parallel to the longitudinal axis of the ways, said rod being rotatable from a position locking the vise on the ways to a position releasing said vise for longitudinal movement including coacting means on the said vise adapted to engage the said rod when it is in the first said position for the purposes of locking the said vise.
